UNITED STATES PATENT OFFICE.

C. H. EMERSON AND J. F. EMERSON, OF NEW YORK, N. Y.

IMPROVED MACHINE FOR MAKING BOLT-HEADS.

Specification forming part of Letters Patent No. 89,211, dated April 20, 1869.

To all whom it may concern:

Be it known that we, C. H. EMERSON and J. F. EMERSON, of the city, county, and State of New York, have invented a new and useful Improvement in Bolt-Heading Machines, of which the following is a full, clear, and exact description, reference being had to the accompanying drawing, forming part of this specification, and in which—

Figure 1 represents a plan of a bolt-heading machine constructed in accordance with our improvement; Fig. 2, a central longitudinal vertical section of the same, and Fig. 3 a transverse section thereof through the line *x* *x* in Fig. 1.

Similar letters of reference indicate corresponding parts.

This our improvement embraces in the one machine a double header for action in concert with grippers and double squaring-jaws, so arranged and operating that the bolt to be headed is first pressed into a conical or rivet-head shape at its end, and afterward squared in a preparatory manner, and subsequently jumped or pressed up to give a rounded finish to the top or back of the head, and then squared again at its sides to complete the head, whereby a most perfect and solid head is formed on the end of the bolt.

Referring to the accompanying drawing, A represents the bed of the machine, and B the driving-shaft carried thereon. On this shaft are hung or arranged cams C, D, E, and F, the offices of which will be explained in their regular order.

The heated bar from which the bolts are to be made is first introduced along an upper groove made in one side of a vertical slot, *b*, running through a front guide, G, and farther introduced or passed through between grippers H H and formers or squaring-jaws I I up to against a top header, J, in or during the back position of the latter. The grippers H H, or one of them, are then made to slide forward for the purpose of holding the bar by means of the cam C, acting against and moving a sliding bar, K, formed of a beveled configuration at its front end. After this the header J is made to advance by the action of the cam D against a sliding stock, L, carrying the top header, J, and a lower header, J'. The top

header, J, which thus first acts against the end of the bar, is so cupped or shaped as that, in its advance stroke, it gives a rivet-head formation to the end of the bar, which formation, it is found from practice, secures a more solid and perfect square or polygonal shaped head on suitable formers being applied to finish the head than any other preparatory formation. The head having been thus preparatorily jumped on the bolt or end of the bar, as shown by red lines in Fig. 2, the heading-stock L retires, and the squaring-jaws I I are made, by the action of the cams E and F on bevel-nosed sliding bars S S, to approach each other and square up the sides of the head by means of upper recesses, *c c*, formed in them. After this the jaws I I retire or open, and also the grippers H H, which enables the workman to shift the bar from the top groove in the guide G to a lower groove therein, when the same operation is gone through as before, only in connection with a lower header, J', and lower recesses, *e e*, in the squaring-jaws I I, the grippers H H first closing to hold the bar or partially-headed bolt; then the header J' coming forward to give a rounded finish to the end of the head, as shown by red lines in Fig. 2, and afterward the jaws I I advancing to finish the squaring up of the sides of the head by the recesses *e e* formed in said jaws, said recesses being somewhat smaller than the upper recesses, *c c*, and the lower header, J', preferably lying a little in advance of the upper header, J.

On the opening of the grippers again the bar or bolt may be turned to repeat the compressing or finishing action by or on a changed position of the surfaces. The griper or grippers, heading-stock, and squaring-jaws, when relieved from being pressed forward by the cams which give to them their timely advance actions, are thrown back or made to recede by means of springs N, O, P, and Q, of any suitable form or character. To prevent damage, however, in case of any irregularity in action of the parts—as, for instance, in case of the squaring-jaws I I not retiring in proper time for the headers J J' to make their advance stroke—the forward portion of the heading-stock L is formed or provided with wedges or inclined surfaces *ff*, which, as the headers advance, act

against inclines *g g*, attached to the sliding jaws *I I*, and force the latter back should they not have previously retired by the action of their springs.

After the bolt has been headed, it is cut off from the bar by any suitable cutter attached to the machine, and in due course a succeeding bolt formed and headed till the bar is worked up.

What is here claimed, and desired to be secured by Letters Patent, is—

1. The combination of the heading-stock *L*, having thereon preparatory and finishing headers *J J'*, constructed substantially as described, with the grippers *II H* and head-squaring jaws

II, formed with upper and lower recesses, *c* and *e*, arranged and operating first to roughly form the head and afterward to finish it, substantially as specified.

2. In combination with the above, the heading-stock *L*, provided with wedges or inclines *ff*, at or near its forward end, and the inclines *g g*, attached to the squaring-jaws *II*, essentially as shown and described, and for the purpose set forth.

C. H. EMERSON.
